FRAME FOR A HELICOPTER

Buford J. Schramm, 244 N. County Club Drive,
Mesa, Ariz. 85201

Filed Oct. 3, 1967, Ser. No. 3,847

Term of patent 14 years

Int. Cl. D12—07

U.S. Cl. D71—1

FIG. 1 is a perspective view of a frame for a helicopter showing my new design;

FIG. 2 is a side elevation; and

FIG. 3 is a top plan view.

I claim:

The ornamental design for a frame for a helicopter, as shown.
